United States Patent Office

Des. 212,847
Patented Dec. 3, 1968

212,847

INCENSE BURNER

Joseph H. Jeitner, Sr., 3944 Richmond St.,
Philadelphia, Pa. 19137

Filed Feb. 26, 1968, Ser. No. 10,727

Term of patent 7 years

(Cl. D23—78)

FIG. 1

FIG. 2.

The dominant features of my design for an incense burner reside in the portions shown in full lines.

I claim:

The ornamental design for an incense burner, as shown and described.
